United States Patent Office

Des. 191,475
Patented Oct. 3, 1961

191,475

MOTION PICTURE PROJECTOR OR SIMILAR ARTICLE

Robert L. Smith, Deerfield, Ill., assignor to Bell & Howell
Company, Chicago, Ill., a corporation of Illinois

Filed Oct. 21, 1960, Ser. No. 62,564

Term of patent 14 years

(Cl. D61—1)

FIG. 1.

FIG. 2.

FIGURE 1 is a perspective view of a motion picture projector or similar article embodying my new design; and

I claim:

The ornamental design for a motion picture projector or similar article, as shown.
